UNITED STATES PATENT OFFICE.

FREDERICK E. KAMPMAYER, SR., AND WILLIAM F. FLEISHER, OF PITTSBURG, PENNSYLVANIA, ASSIGNORS OF ONE-EIGHTH TO CHARLES KAMPMAYER, SR., OF PITTSBURG, PENNSYLVANIA, AND SEVEN-EIGHTHS TO SAID FREDERICK E. KAMPMAYER, SR.

MAIL-DELIVERING DEVICE.

No. 895,272.

Specification of Letters Patent.

Patented Aug. 4, 1908.

Application filed December 13, 1907. Serial No. 406,348.

To all whom it may concern:

Be it known that we, FREDERICK E. KAMPMAYER, Sr., and WILLIAM F. FLEISHER, citizens of the United States of America, residing at Pittsburgh, in the county of Allegheny and State of Pennsylvania, have invented certain new and useful Improvements in Mail-Delivering Devices, of which the following is a specification, reference being had 10 therein to the accompanying drawing.

This invention relates to a mail delivering device, particularly designed for railway cars.

The primary object of our invention is, to 15 provide novel means within a car for quickly and safely discharging mail.

Another object of this invention is to provide a novel trough or catching structure into which the mail can be precipitated by 20 our delivering device.

To this end, we provide a car with a simple and inexpensive tilting platform, and employ a latch for normally holding the platform in a horizontal position, while the same is being 25 loaded with mail bags or pouches. In connection with the tilting platform, we use a trough or catching structure, which is located in close proximity to the track over which the mail car travels. This trough or catching 30 structure is provided with projecting pins adapted to be impinged by the latch of the tilting platform to precipitate the mail upon the platform into the trough at a predetermined time.

By the novel construction of our device we 35 prevent injury to mail bags and insure a delivery at a predetermined time.

The detail construction entering into our invention will be presently described and 40 then specifically pointed out in the appended claims.

In the drawing: Figure 1 is an elevation of our device as applied to a mail car, illustrating the tilting platform thereof in a horizontal 45 position, Fig. 2 is a similar view illustrating the platform as tilted, Fig. 3 is a plan of our device, the car and receiving trough being partly broken away, and Fig. 4 is a diagrammatic view illustrating the device in 50 front elevation.

To put our invention into practice, we provide a car 1 with two side frames 2, these side frames being secured in the door-way 3 of the car upon the floor 4 thereof. Trun-

nioned between the side frames 2 is a tilting 55 platform 5, said platform being covered by a metallic plate 6, constituting a weight upon the outer edge of the platform, which together with the weight of mail bags placed thereon is sufficient to quickly tilt the platform. 60

To normally maintain the platform in a horizontal position, we provide the under- face thereof adjacent to the inner edge with a fulcrumed latch, the shorter arm 7 thereof 65 engaging under a keeper 8 mounted upon a block 9 arranged between the side frames 2. The long arm 10 of the latch extends to the door-way 3 and is bent downwardly to pro- vide a projection 11, the object of which will 70 presently appear.

At the outer side of the track 12 upon which the car 1 travels, we construct an ob- long trough or catching structure, this trough comprising inclined end walls 13 con- 75 nected by an arched outer wall 14, and an inner wall 15, the latter carrying a chute 16. These walls are constructed between posts 17, the inner posts being provided with pins or projections 18 adapted to contact with 80 the projection 11 of the fulcrumed latch.

Assuming that mail has been placed upon the tilting platform 5 to be delivered into the trough or catching structure, the ful- crumed latch of the tilting platform will be 85 released immediately upon the projection 11 striking the pin 18 of the trough or catch- ing structure. When the latch swings clear of the keeper 8, as illustrated in dotted lines in Fig. 3, the weighted outer edge of the 90 platform causes said platform to tilt auto- matically by gravity, as illustrated in Fig. 2, precipitating the mail bags carried thereby to the chute 16, and from there into the trough or structure. From this structure 95 the mail bags are easily removed by virtue of the arched outer wall 14.

To insure a free movement of the tilting platform, we cut away the floor 4 of the car, as at 19. 100

From the foregoing description taken in connection with the drawings, it will be apparent that our device can be easily ap- plied to the door-way of the car and that mail can be handled from both ends thereof. 105 The device as carried by a car can be con- structed of light and durable metal, while the trough or catching structure can be made

of wood, metal or similar material. Owing to the fact that the tilting platform is released immediately at one end of the trough or structure, it will not be necessary for the 5 trough or structure to be of a great length, as the mail bags carried by the tilting platform will be immediately deposited in the trough.

We do not care to confine ourselves to the 10 type of car in connection with which the device is used, and reserve the right to make such structural changes as are permissible by the appended claims.

Having now described our invention what 15 we claim as new, is:—

1. In a mail delivering device, the combination with a car, of side frames fitting in the door-way thereof, a metal covered platform trunnioned between said frames, 20 a fulcrumed latch carried by said platform, a keeper mounted in said car for engaging one end of said latch, the opposite end of said latch projecting from said car, a trough located adjacent to the path traveled by said 25 car, said trough having an arched wall and a chute, and a projecting pin carried by said trough for contacting with said latch and releasing said tilting platform, substantially as described.
- 30 2. In a mail pouch delivering apparatus, a gravity-tilting support, a latch carried by the support, a keeper engaged by said latch, said latch and keeper normally holding the

support against tilting movement, and means exterior of the car in which the support is arranged for engagement with the latch to disengage same from the keeper to permit tilting movement of the support. 35

3. In a mail pouch delivering apparatus, supports arranged within a car, a pouch support trunnioned in said supports to tilt by gravity towards the door of the car, and means for normally securing the pouch support against tilting movement. 40

4. In a mail pouch delivering apparatus, a pouch support arranged within a car to tilt by gravity automatically to discharge a mail pouch therefrom, a fulcrumed-latch carried by the support having one end thereof extending outside the car, a keeper arranged within the car in position to be engaged by the other end of said latch whereby the support is normally held in a horizontal position and against tilting movement, and means for engagement with the extending end of 55 said latch for disengaging the other end thereof from the keeper to permit tilting movement of the pouch support.

In testimony whereof we affix our signatures in the presence of two witnesses.

FREDERICK E. KAMPMAYER, SR.
WILLIAM F. FLEISHER.
